US00D414503S

United States Patent [19]

Katoh

[11] Patent Number: Des. 414,503

[45] Date of Patent: ** Sep. 28, 1999

[54] **MACHINE FOR FORMING A SEMICONDUCTOR WAFER FILM**

[75] Inventor: **Susumu Katoh**, Yamanashi-ken, Japan

[73] Assignee: **Tokyo Electron Limited**, Tokyo, Japan

[**] Term: **14 Years**

[21] Appl. No.: **29/085,326**

[22] Filed: **Mar. 20, 1998**

[30] **Foreign Application Priority Data**

Sep. 24, 1997 [JP] Japan 9-68687

[51] **LOC (6) Cl. 15-09**

[52] **U.S. Cl. D15/144.1; D10/75**

[58] **Field of Search** D10/75; D15/144.1; 250/492.2

[57] **CLAIM**

The ornamental design for machine for forming a semiconductor wafer film, as shown.

DESCRIPTION

FIG. 1 is a front elevational view of machine for forming a semiconductor wafer film, showing my new design;

FIG. 2 is a right side elevational view thereof;

FIG. 3 is a left side elevational view thereof;

FIG. 4 is a rear elevational view thereof;

FIG. 5 is a top plan view thereof; and,

FIG. 6 is a bottom plan view thereof.
